ALVIN M. MOTHERSHEAD, OF INDIANAPOLIS, INDIANA.

Design No. 4,895, dated May 9, 1871.

DESIGN FOR THE PLATES OF A COOKING-STOVE.

The Schedule referred to in these Letters Patent and making part of the same.

I, ALVIN M. MOTHERSHEAD, of Indianapolis, in the county of Marion and State of Indiana, have invented and produced a new and original Design for the Plates of a Cooking-Stove, of which the following is a specification.

The nature of my design is fully represented in the accompanying photographic illustrations of a cooking-stove, in which my said design is embodied.

The distinguishing features of my said ornamental design consist of the devices a a' b c, formed in bass-relief upon a panel, k, on one or more of the doors or plates D E F H of a stove, the same being arranged together and fashioned so as to appear as represented in the aforesaid photographs.

Claim.

I claim as my invention—

The design for a plate or plates of a cooking-stove, as herein shown and described.

ALVIN M. MOTHERSHEAD.
